US00D549975S

(12) **United States Design Patent** (10) Patent No.: **US D549,975 S**
Fancelli (45) Date of Patent: **** Sep. 4, 2007**

(54) **CHAIR**

(75) Inventor: **Paolo Fancelli**, Zurich (CH)

D514,338 S * 2/2006 Bellin D6/366

(73) Assignee: **Stoll Giroflex AG**, Koblenz (CH)

* cited by examiner

(**) Term: **14 Years**

Primary Examiner—Robert M. Spear

Assistant Examiner—Katrina A. Kile

(74) Attorney, Agent, or Firm—Greenblum & Bernstein, P.L.C.

(21) Appl. No.: **29/221,405**

(57) **CLAIM**

(22) Filed: **Jan. 18, 2005**

I claim the ornamental design for a chair, as shown and described.

(30) **Foreign Application Priority Data**

Jul. 19, 2004 (WO) DM/065 622

DESCRIPTION

(51) **LOC (8) Cl.** **06-01**

FIG. 1 is a perspective view of a chair my design;

(52) **U.S. Cl.** **D6/366**

FIG. 2 is a front view of the design;

(58) **Field of Classification Search** D6/356, D6/334, 335, 364-367, 374, 375, 379, 500-502; 297/284.4, 411.36, 452.21, 452.29, 452.3, 297/452.35, 452.38

FIG. 3 is a back view of the design;

See application file for complete search history.

FIG. 4 is a right side view of the design;

(56) **References Cited**

FIG. 5 is a left side view of the design;

U.S. PATENT DOCUMENTS

FIG. 6 is a top view of the design; and,

D247,463 S * 3/1978 Muller-Deisig D6/366

FIG. 7 is a bottom view of the design.

D437,132 S * 2/2001 Nagamitsu D6/366

Any surfaces of the design not shown, including interior surfaces, form no part of the claimed invention.

D446,955 S * 8/2001 Zemp D6/366

1 Claim, 7 Drawing Sheets
